WARP CONTROL IN AXMINSTER LOOMS

Clyde E. Brown, Grafton, Mass., assignor to
Crompton & Knowles Loom Works, Worcester,
Mass., a corporation of Massachusetts

Application July 15, 1940, Serial No. 345,539

12 Claims. (Cl. 139—2)

This invention relates to improvements in Axminster looms and it is the general object of the invention to provide mechanism which will facilitate movement of the tuft yarns over hooks on the cloth board.

Certain types of Axminster looms employ a cloth board formed with upright hooks over which the picks of filling and the tuft yarns are beaten. When the height of the pile tufts is comparatively low a short hook can be employed, but when it is desired to use a fabric having a higher tuft it is desirable to use longer hooks. The same loom may, however, be called upon to weave fabrics having high pile at one time and low pile at another and in order to accommodate this condition the longer hooks are used as a permanent part of the loom structure. The reed moves the weft and tufts to a position in front of the hooks and must lift the weft to a relatively high point above the cloth board. This lifting is resisted by the downward pull of the lower warp shed. It is accordingly an important object of my present invention to provide mechanism which will lift the warp shed at the time of beat-up to assist the reed to lift the tufts over the hooks.

The binder warp threads extend rearwardly from the hooks through the reed on the lay to the vertically reciprocating harness frames. It is another object of my invention to provide a lifter bar on the lay to be raised periodically as the reed approaches its front position to lift the bottom warp shed to lessen the downward pull on the fell of the cloth, thereby assisting the reed to beat the shots of weft over the hooks. I prefer to mount the rod for movement relatively to the lay and have it actuated by the lay as the latter moves forwardly.

In wide Axminster looms the aforesaid bar would have a tendency to sag unless supported at intermediate points between its ends. It is a further object of my invention to provide lifters for the ends of the bar and additional intermediate lifters, together with coordinated actuating mechanisms to require the ends and central lifters to raise all parts of the bar the same distance.

With these and other objects in view which will appear as the description proceeds, my invention resides in the combination and arrangement of parts hereinafter described and set forth.

In the accompanying drawings, wherein a convenient embodiment of my invention is set forth, Fig. 1 is an end elevation of a portion of an

Axminster loom made according to my present invention,

Fig. 2 is a vertical section slightly reduced on line 2—2 of Fig. 1 looking forwardly toward the rear of the lay and showing the warp lifting bar 5 and control mechanism therefor,

Fig. 3 is a diagrammatic view similar to a portion of Fig. 1 on a reduced scale and showing the lay on front center position with the invention operative to raise the lower warp shed, and 10

Figs. 4 and 5 are enlarged detail vertical sections on lines 4—4 and 5—5, respectively, of Fig. 2.

Referring to the drawings, I have shown a loom frame 10 having a cloth board 11 provided with 15 a series of upright hooks 12 from which extend in a downwardly and rearwardly direction tuft guiding surfaces 13. The lay L is mounted for rocking movement on a shaft 15 which is oscillated by well-known mechanism not shown. The 20 shaft is mounted in several bearings one of which is shown at 16 in Fig. 1 and carries a reed R between the dents of which extend the binder warp threads which form the upper and lower warp sheds W' and W², respectively. The warp 25 threads extend forwardly between the hooks 12 to be connected to the fabric at the fell in front of the hooks and are controlled as to their vertical positions by harness frames H. Formed as a usual part of the loom frame is a beam 17 30 which extends across the loom and is fastened to the frame 10.

My invention is used more particularly though not necessarily in connection with looms adapted for the weaving of fabrics having the pattern 35 showing on their back. To assist in the guiding of the pile forming yarns up the surfaces 13 there is provided a series of plates 20 mounted on the lever 21 which rocks about a shaft 22. A rod 23 pivoted at 24 to the lever 21 is caused to 40 rise and fall by mechanism not shown herein to move the plates 20 about the shaft 22. The plates move through the spaces 25 between the hooks 12 and register with the dents of the reed R to define guide aisles for the tuft yarns, as 45 described for instance in prior Patent No. 1,958,129.

The loom operates with a series of tube frames one of which is indicated at T having a spool S wound with the variously colored tuft yarns Y 50 which extend through the tubes 30 and project downwardly from the latter as indicated in Fig. 1. The tube frame is mounted on an operating arm 31 of well-known construction. Front and back cutting blades 32 and 33, respectively may be of 55

the usual form and are separated as indicated in Fig. 1 to permit movement of the tube frame T to tuft forming position.

As is usual in Axminster looms the weft is laid 5 by a needle N which is moved into and out of the shed formed by the warp threads W' and W² while the reed is in rear position. The needle lays a double pick which is interlaced with the weft of a selvage shuttle not shown on that side 10 of the loom opposite the side from which the needle enters the shed.

In operation, the lay moves back and forth and the needle enters the shed when the reed is 15 in the position shown in Fig. 1. The needle is then moved out of the shed and the reed moves forwardly to force the filling indicated at F up the inclined surfaces 13 and over the hooks 12, as shown in Fig. 3. If the fabric being woven is 20 so-called three-shot Axminster the tube frame will be manipulated once for every three insertions of the weft needle and will dip the color yarns through the warp shed while the lay is in rear position. The tube frame is then rocked forwardly and a shot of filling laid behind the 25 depending tuft yarns, after which the reed moves forwardly with the guide plates. As the reed continues to move forwardly the yarns Y move through the guide aisles formed by plates 20 and up the inclined surfaces 13 and over the hooks 30 together with the weft which was laid behind the tuft yarns. The tube frame is then raised sufficiently to draw off enough yarn for the next row of tufts and the cutting blades sever the tuft yarns from the spool S.

35 The matter thus far described is well-known and of itself forms no part of my present invention. The hooks 12 are relatively high so that they can cooperate properly with high pile tufts. Reference may be had to the previously mentioned patent for a further description of the construction and operation of the parts already described.

The length or height of the hooks 12 renders 40 desirable some means for assisting the reed to 45 push the weft and tuft yarns over the hooks. The bottom of the cloth normally rests on surface A of the cloth board and must be raised substantially the height of the hooks when the weft moves over them. My invention relates to 50 mechanism for accomplishing this result. As seen particularly in Fig. 2 I provide a bar 40 which extends above the lay but under the bottom warp shed W². This bar is mounted on a plurality of arms 41 pivoted as at 42 to rearward 55 extensions 43 of the lay L. Certain of these arms, particularly those at the ends of the bar, lie outside the selvages of the fabric being woven and are provided with rolls 45 positioned for engagement with fixed cams 46. There will be one cam 60 46 at each end of the loom and each will be formed with an upwardly and forwardly inclined cam face 47 formed substantially as shown in Fig. 1 and placed for engagement with the roll 45 corresponding thereto.

65 Each cam 46 is mounted on a bracket 50 having a foot 51 bolted to the beam 17. Slots 52 in the cam 46 receive bolts 53 which extend into the bracket 50 to hold the cam rigidly but in adjusted position with respect to the bracket 50. 70 An additional support for the bracket may be provided as indicated in Fig. 1 in the form of a foot 55 held to the support by bolts 56 which extend through a slot 57 in the foot. The bottom of the foot is formed with a shoe 58 which rests 75 on the shaft 15 for support. By means of the

adjustments described the bracket 50 can be held in fixed position capable of supporting considerable downward pressure, and the cam 46 can be given a limited vertical adjustment.

In the operation of that part of my invention 5 already described forward motion of the lay will cause the rolls 45 to move up the cam faces 47, from the position of Fig. 1 to that of Fig. 3, thereby lifting the ends of the bar 40 to elevate the bottom warp shed W². This raising of the 10 warp shed occurs as the reed approaches its front position and there is therefore a relative elevation of the warp shed with respect to the hooks 12, a condition which reduces the downward pull of the bottom shed on the fell and assists the reed 15 to push the weft and the tuft yarns over the hooks.

In wide looms it is desirable to provide additional lifting mechanism for the bar 40 intermediate the selvages of the fabric. To accomplish 20 this result I provide a series of rolls 60 each mounted on an arm 61 pivoted at 62 to a support 63 secured to an intermediate lay arm 64 which is secured to shaft 15 and oscillates with the reed. For each roll 60 there is provided a fixed cam 65 25 which derives its support from auxiliary brackets 66. Each bracket 66 is fixed to a bearing 68 for the lay shaft 15 mounted on a transverse girt 69. The cams 65 are provided with upwardly and forwardly inclined surfaces 67 corresponding to 30 the surfaces 47 but somewhat steeper than the latter due to the fact that the rolls 60 and cams 65 which cooperate with them are nearer the axis of shaft 15 than are the rolls 45 and their cams 47. Extending upwardly from each arm 61 35 is a rod 70 having a cup bearing 71 in which the bar 40 rests and can rotate, see Fig. 5. The rods or links 70 are distributed along the length of the bar 40 and enough of them will be employed to prevent substantial bending of the bar 40 during 40 the warp lifting operation.

At the same time that the rolls 45 are moving up their cams 47, as already described, the rolls 60 will move up the cams 65 to the position shown 45 in Fig. 3, thereby exerting an upward thrust on the rods 70 to raise the intermediate parts of the bar 40 between the rolls 45. The rolls 45 and 60 will engage their cams at substantially the same time during the forward motion of the lay and the cams will be so designed that the rolls 45 and 60 will rise at substantially the same rate, hence the bar 40 will be lifted by a series of uniform and coordinated forces imparted to it throughout its length and acting to maintain the bar substantially straight and prevent downward bending thereof. 55

As the lay approaches front center the rolls are high on their cams with the result that the bar 40 is raised from a relatively low position shown 60 in Fig. 1 to the comparatively high position in Fig. 3 to elevate the bottom shed W². The effect of raising bar 40 is to reduce the downward pull on the fell of the cloth by the warp forming the lower shed W², thereby reducing the amount of 65 force required to push the shots of weft and the tuft yarns over the hooks 12. It will be understood that the cams are so placed that bar 40 does not start to rise until after the needle N is out of the shed. As the lay recedes the pressure of the bottom shed downwardly on bar 40 70 causes the rolls to be restored to their low positions when the lay is in the back center position shown in Fig. 1, and when in this low position bar 40 exerts no upward force on the binders W², see 75

Figs. 4 and 5, and the shed is wide open for reception of the needle:

While I have shown a bar under the warp shed as one embodiment of my invention, I do not wish 5 to be limited to that specific construction. It is sufficient if there is a relative vertical motion of the hooks and cloth brought about by means additional to the reed to assist the latter to push the weft and tufts over the hooks. The effect of 10 the invention is to permit the reed to raise the weft by the expenditure of less force than would be required if the reed alone were required to raise the weft over the hooks unassisted and in the usual manner.

15 From the foregoing it will be seen that I have provided a simple means for lessening the downward force exerted on the weft and tuft yarns which are being beaten over the hooks 12, thereby permitting the use of a cloth board having 20 relatively high hooks. As shown herein this result is accomplished by means of the bar 40 which is raised during forward beating of the lay to move the warp shed W² upwardly. It will also be seen that the rolls are mounted on the 25 lay and that the actuating force for raising the bar 40 is derived from the lay as the same advances. It will further be seen that the cams 46 and 67 are so constructed as to compensate for the differences in their distances from the 30 shaft 15, the lower cams 67 being somewhat steeper than the upper cams 46 so that the lesser forward motion of the rolls 60 will effect the same upward motion of the intermediate ends of the bar as that caused by the rolls 45 35 when the latter rise on the cams 46.

Having thus described my invention it will be seen that changes and modifications may be made therein by those skilled in the art without departing from the spirit and scope of the invention and I do not wish to be limited to the details herein disclosed, but what I claim is:

1. In an Axminster loom having a notched cloth board with upstanding hooks behind the fell of the cloth and having warp threads extending between the hooks to be raised and lowered to form top and bottom sheds for the insertion of weft, a lay movable toward and from the cloth board, a reed to move the weft over said hooks to the fell of the cloth, and means 45 under the bottom shed operative on the beat of the lay toward the cloth board to engage and raise said bottom shed and thereby reduce the downward force which the bottom shed exerts on the fell of the cloth.

55 2. In an Axminster loom having a notched cloth board with upstanding hooks and having warp threads extending between the hooks to be raised and lowered to form top and bottom sheds for the insertion of weft, a lay movable toward and from the cloth board, a reed carried by the lay to move the weft over the hooks to the fell of the cloth, and means under the bottom warp 60 shed acting in timed relation with the movement of the lay toward the hooks to engage and lift the bottom shed of warp threads to assist the reed to move the filling over said hooks.

3. In an Axminster loom having a notched cloth board with upstanding hooks behind the fell of the cloth and operating with warp threads 70 extending between the hooks to be raised and lowered to form top and bottom sheds for the insertion of weft, a lay movable toward and from the hooks, a reed carried by the lay to move the weft over the hooks to the fell of the cloth, 75 a bar extending under the lower shed and sup-

ported by and movable relatively to the lay, and means operative during forward movement of the reed toward the hooks to cause upward movement of the bar against the lower shed of warp threads to elevate the latter, thereby reducing 5 the downward force exerted by the bottom shed of warp threads on the fell of the cloth and assist the reed in forcing the weft over the hooks.

4. In an Axminster loom having a notched cloth board with upstanding hooks behind the fell of the cloth and having warp threads extending between the hooks to be raised and lowered to form top and bottom sheds for the insertion of weft, a lay movable toward and from the cloth board, a reed carried by the lay to move the weft over the hooks and to the fell of the cloth, a bar extending under the bottom shed of warp threads, means pivoted to the lay and supporting the bar, and fixed means effective during movement of the lay toward the cloth 20 board to elevate the bar and lift the lower shed of warp threads to lessen the downward force exerted by the lower shed of warp threads on the fell of the cloth.

5. In an Axminster loom having a notched cloth board with upstanding hooks behind the fell of the cloth and operating with warp threads extending between the hooks to be raised and lowered to form top and bottom sheds for the insertion of weft, a lay movable toward and from the cloth board, a reed carried by the lay to move the weft to the fell of the cloth over the hooks, a bar extending under the lower shed of warp threads, means to support the bar for vertical motion relatively to the lay, fixed cam means, 30 35 and means to connect the cam means and the bar to cause upward movement of the latter due to forward movement of the lay when the latter approaches the cloth board to reduce the downward force exerted by the lower shed of warp threads on the fell of the cloth.

6. In an Axminster loom having a notched cloth board with upstanding hooks behind the fell of the cloth and operating with warp threads extending between hooks to be raised and lowered to form top and bottom sheds for the insertion of weft, a lay movable toward and from the cloth board, a reed carried by the lay to move the weft over the hooks to the fell of the cloth, a bar extending under the lower shed of warp threads, supporting arms for the ends of the bar pivoted to the lay and movable vertically relatively to said lay, a cam fixed adjacent each side of the loom to engage the supporting arms, intermediate cams fixed with respect to 45 the loom frame and distributed across the loom, and pivoted intermediate arms to be moved by the intermediate cams, links extending from said pivoted arms to intermediate points along the bar between the ends thereof, forward movement of the lay causing said supporting and pivoted arms to be raised by their respective cams thereto to elevate the bar and raise the lower shed of warp threads to reduce the downward force exerted by said lower shed on the fell of the 50 55 cloth.

7. The structure set forth in claim 6 together with means to pivot said intermediate arms to the lay.

8. The structure substantially as set forth in 70 claim 6 wherein said cams for the intermediate arms are nearer the axis of the lay than the cams for the supporting arms and wherein said cams act through their respective arms to effect substantially the same amount of upward mo- 75

tion of the ends of the bar and the intermediate points thereof during the latter part of the angular motion of the lay toward the cloth board.

9. In an Axminster loom having a cloth board with spaced upstanding hooks behind the fell of the cloth and having warp threads extending between the hooks and rearwardly to be raised and lowered to form top and bottom warp sheds for the insertion of weft, a lay movable toward and from the cloth board, a reed on the lay having dents to pass between the hooks on the forward beat of the lay to a position in front of the hooks to beat the weft over the hooks and into the fell of the cloth, a bar extending under the bottom warp shed, a supporting rod for the bar depending therefrom, and means to raise the rod during forward motion of the lay to elevate the bar while in contact with the bottom shed to lift the latter and thereby reduce the downward pull of said bottom shed on the fell of the cloth and assist the reed to move the weft over the hooks.

10. In an Axminster loom having a cloth board with spaced upstanding hooks behind the fell of the cloth and having warp threads extending between the hooks and rearwardly to be raised and lowered to form top and bottom warp sheds for the insertion of weft, a lay movable toward and from the cloth board, a reed on the lay having dents to pass between the hooks on the forward beat of the lay to a position in front of the hooks to beat the weft over the hooks and into the fell of the cloth, a bar extending under the bottom warp shed, a supporting rod for the bar depending therefrom, and means to raise the rod during forward motion of the lay to elevate the bar while in contact with the bottom shed to lift the latter and thereby reduce the downward pull of said bottom shed on the fell of the cloth and assist the reed to move the weft.

11. In an Axminster loom having a cloth board with spaced upstanding hooks behind the fell of the cloth and having warp threads extending be-

tween the hooks and rearwardly to be raised and lowered to form top and bottom warp sheds for the insertion of weft, a lay movable toward and from the cloth board, a reed on the lay having dents to pass between the hooks on the forward beat of the lay to a position in front of the hooks to beat the weft over the hooks and into the fell of the cloth, a bar extending under the bottom warp shed, a supporting rod for the bar depending therefrom, and means to raise the rod during forward motion of the lay to elevate the bar while in contact with the bottom shed to lift the latter and thereby reduce the downward pull of said bottom shed on the fell of the cloth and assist the reed to move the weft over the hooks.

12. In an Axminster loom having a cloth board with spaced upstanding hooks behind the fell of the cloth and having warp threads extending between the hooks and rearwardly to be raised and lowered to form top and bottom warp sheds for the insertion of weft, a lay movable toward and from the cloth board, a reed on the lay having dents to pass between the hooks on the forward beat of the lay to a position in front of the hooks to beat the weft over the hooks and into the fell of the cloth, and means in addition to the reed to effect movement of the fell of the cloth upwardly relatively to the hooks to assist the reed to move the weft over the hooks, said means including an arm member and a cam member to cooperate therewith during forward motion of the lay, one of said members being mounted on and moving with the lay.

CLYDE E. BROWN.
